REEL

Charles E. Bieber, Roselle, N.J., assignor to Monroe Calculating Machine Company, Orange, N.J., a corporation of Delaware

Filed Dec. 23, 1959, Ser. No. 861,509
9 Claims. (Cl. 242—71.8)

This invention pertains to reels or spools for web material such as inked ribbons.

It is an object of the invention to provide a reel having novel means for securely holding a roll of web material thereon.

It is a further object to provide a reel having gripping means for securely holding a roll of web material.

It is a further object to provide a reel having gripping means for securely holding a roll of web material, said reel including novel means whereby the gripping means can be readily and easily operated to grip or release the roll.

In the illustrative embodiment of the invention disclosed herein, the reel comprises a pair of spaced side plates detachably coupled together. A suitable latching means maintains the side plates in coupled relation. Mounted on the outside face of one of the side plates is a pair of levers, disposed on opposite sides of a diametral line of the plate. Each of the levers carries an inwardly extending pin adapted to grip the inside of the roll of web material carried by the reel. Spring means acting on the levers resiliently urge the pins into gripping engagement with the roll. The spring means are also utilized to urge the aforementioned latching means to operated position. Each lever also includes a suitable finger piece which may be grasped to rock the gripping pins away from engagement with the roll to release the latter.

Other objects and advantages of the invention will be readily apparent from the following detailed description when read in connection with the accompanying drawings, in which:

FIG. 1 is a side elevational view of the reel of the present invention.

FIG. 2 is a sectional view taken on line 2—2 of FIG. 1.

FIG. 3 is a sectional view taken on line 3—3 of FIG. 2.

Referring now to the drawing, reference numeral 1 designates the roll of web material carried by the reel. The type of web material for which the reel of the present invention is primarily intended is an inked ribbon having a base layer of paper, "Mylar," or like material. It will be understood, however, that the reel can be used for any desired type of web material, e.g., punched tape, magnetic tape, motion picture film, etc. The roll 1 includes the usual annular core 2 of cardboard or the like upon which the web material is wound.

The reel or spool of the present invention includes a pair of substantially identical spaced side plates 3 and 4. The plates are disc-like in form and include the usual circular cutouts 3a, 4a. One of the plates, 3, is rotatably mounted on a suitable fixed support means 5. The other plate, 4, which carries the roll of web material, is normally coupled to the fixed plate for rotation therewith. Means is provided whereby the outer plate 4 may easily be removed for mounting thereon a roll of the web material or for removing therefrom the empty core of a used roll, as will be described subsequently.

Plate 3 is mounted as follows. As best seen in FIG. 2 a stud 6 threaded along a portion of its length is screwed through a correspondingly threaded opening in the supporting member 5. Supporting member 5 may be a framing plate of any suitable business machine such as a typewriter, adding-listing machine, or the like. The inner end of the threaded portion of the stud terminates

2

at a narrow integral flange 7 of the stud, which abuts one face of the support member 5. A nut 10 threaded on stud 6 engages the opposite face of the support member and holds the stud rigidly in place.

5 The side plate 3 is rigidly secured, as by being spun thereon, to a sleeve-like hub member 11. Journalled for rotation in a central longitudinal bore 12 of stud 6 is an elongated shaft 13. The hub member 11 is mounted on shaft 13 and is rigidly coupled thereto by a pin 14 which is fast with the shaft and which extends through closely fitting circular openings in the hub member.

Accordingly, it will be seen that shaft 13, hub 11, and plate 3 are rigidly coupled together as a unit for rotation about the axis defined by the bore 12 of stud 6. Shaft 13 is adapted to be rotatably driven by any suitable means. For example, a cup-shaped pulley 15 may be rigidly secured to the shaft by a set screw 16 and may be driven by a belt 17 actuated by any suitable power source. Undesirable lengthwise movement of the shaft in either direction is prevented by abutment of the inner face of the base of the cup-shaped pulley with one end of stud 6, and abutment of the side plate 3 with the opposite end of the stud.

Customarily, the reel is driven only if it is used as a take-up reel. When it is used as a supply reel, there will usually be no need to provide a special drive means for the reel, since in such cases pulling the ribbon from the reel to feed the ribbon will rotate the reel.

Rigidly secured to the removable side plate 4 is a coaxial inwardly extending collar 20 whose inner diameter is such that it may be slid over the hub 11 of plate 3. The collar 20 is provided with two pairs of diametrically opposed slots 21 which extend inwardly from the free end thereof and are adapted to receive the outer end portions of pin 14 which extend radially beyond the hub 11. This pin and slot arrangement couples the side plates 3 and 4 together for conjoint rotation. One pair of opposed slots 21 would of course be sufficient but several angularly spaced pairs are provided to facilitate mounting of the side plate by reducing the amount of turning which the operator will have to do to line the slots up with pin 14.

The removable side plate 4 is releasably held in assembled relation with plate 3 by means of a latch 22. Latch 22 comprises a flat strip of material lying against the outside face of plate 3. A pair of headed pins 23 secured to plate 3 along a diametral line thereof are slidably received in aligned elongated slots 24 of the latch whereby the latter is allowed limited longitudinal movement. Adjacent its center, latch 22 is provided with a circular opening 25. As best seen in FIG. 2, the left-hand end portion of shaft 13 is provided with a narrow groove 26. The axial width of this groove is slightly greater than the thickness of latch 22. When the reel is in assembled condition, the free (right) end of collar 20 abuts the inside face of plate 3 and thereby determines the spacing between the two plates 3 and 4. The axial location of groove 26 on shaft 13 is such that latch 22 will now be aligned with the groove. Tension springs 27, 28 (FIG. 1) are respectively secured to integral laterally bent tongues 30, 31 provided at one end of the latch, and urge the latter toward the right in FIG. 1 whereby a portion of the edge of opening 25 enters the groove and engages the base thereof. Accordingly, plate 4 will be held latched against axial movement away from plate 3 by the side wall of the groove.

To release the latch for removal of plate 4, a laterally bent lug 32 provided at the opposite end of the latch from tongues 30, 31 is grasped and moved radially inwardly toward the center of plate 4 against the tension of springs 27 and 28. This will move the edge of open-

ing 25 out of groove 26 whereupon plate 4 is free to be slid axially away from plate 3 for disassembly.

The means whereby the roll of web material is releasably held on plate 4 will now be described. Rigidly secured to plate 4 is a number, in the present case four, of identical inwardly extending pins 33. Hereinafter, these pins are referred to as "fixed" pins meaning that they are fixed relative to plate 4. The centers of the pins lie along a circle whose center coincides with the center of plate 4 and collar 20. The radius of the circle along which the pins lie, and the diameter of the pins themselves is such that the roll 1 may easily be slid over the pins, the core 2 of the roll being loosely supported on the pins. It will be understood that the roll will be introduced first over the free ends of the pins and will then be shifted axially by the operator until one side face of the roll engages the inside face of plate 4.

The roll is held securely but releasably on plate 4 by a pair of diametrically opposed movable pins 34, 35 substantially identical with the fixed pins 33. Each of the movable pins 34, 35 is rigidly secured to the longer arm of one of two respective bell cranks 36, 37. The two bell cranks are respectively pivotally mounted on side plate 4 by means of pivot pins 40 and 41. The pins 34, 35 extend axially inwardly in the same direction as pins 33 through apertures 42, 43 of plate 4, the outer edge portions of the apertures serving to limit the outward movement of the pins.

Referring to FIG. 1, it will be seen that the longitudinal axis of latch 22 lies on a diametral line of plate 4 and the bell cranks are disposed on opposite sides of the latch symmetrically with respect to the same diametral line. Earlier it was mentioned that the latch 22 is urged to latching position by the two springs 27, 28. These same springs are also utilized to rock the bell cranks about their respective pivot axes whereby the pins 34, 35 carried thereby are urged outwardly to grip core 2 to securely hold the roll 1 on plate 4. For this purpose spring 27 is connected to an upstanding lug 44 of bell crank 36 and spring 28 is similarly connected to an upstanding lug 45 of bell crank 37. The better to grip the inside face of core 2, all the pins 33, 34 and 35 are provided with knurling as shown in FIG. 2. To facilitate manipulation of the bell cranks, the free ends of their longer arms are bent laterally to provide finger pieces 46, 47.

It is believed that the manner of using the reel of the present invention will now be apparent from the foregoing description. Under the influence of springs 27, 28, the movable pins 34, 35 will be urged outwardly to firmly engage the inside face of core 2 of roll 1 and hold it securely against rotation relative to plate 4. When it is desired to remove the core 2 of a depleted roll, latch 22 is disengaged from groove 26 on shaft 13 to allow plate 4 to be dismounted. To release the core, the operator grasps finger pieces 46, 47 and urges them toward each other, rocking bell crank 36 counterclockwise and bell crank 37 clockwise as viewed in FIG. 1 to disengage pins 34, 35 from the core. With the operator holding the bell cranks in these respective positions, the core of the used roll may be moved and a new roll including a core may be substituted. Thereafter, upon the operator releasing the bell cranks, springs 27 and 28 will once again move the pins into gripping engagement with the core of the new roll. Plate 4 containing the new roll is then reassembled with plate 3 by placing collar 20 on hub 11, aligning an opposed pair of the slots 21 with pin 14, and then shifting the collar toward plate 3 until it engages the inside face of the latter plate.

In order to allow plate 4 to be then remounted, latch 22 is manually shifted longitudinally and held in open position against the tension of springs 27, 28. Latch 22 is then released by the operator to move into latching relation with shaft 13.

The herein described preferred embodiment of the invention includes the fixed pins 33 which are fixed rela-

tive to plate 4, since it has been found that they aid in properly centering the roll 1 on plate 4. Furthermore, since the outwardly directed gripping forces exerted by the two respective movable pins 34, 35 on core 2 will never be precisely equal, the inside face of the core will bear against a pair of the pins 33, whereby the latter aid in gripping the core and holding it securely relative to plate 4. However, it will be understood that in particular applications, less than four fixed pins may be used and in fact the fixed pins might be dispensed with altogether. This will of course depend on among other things, the rigidity of the core and the need for precisely centering the roll.

Also, only one movable pin could be used in conjunction with one or more fixed pins.

While this specification sets forth in detail the present and preferred construction of the invention, many modifications and variations may be made without departing from the spirit and scope of the invention as defined by the appended claims. It is accordingly intended that the disclosure of one specific embodiment of the invention be illustrative only and not limitative of the claims.

I claim:

1. In a reel for holding a roll of web material, said reel including spaced side plates between which said roll is disposed; means for gripping said roll to securely hold it on said reel, said gripping means including a gripping member mounted on said reel for movement toward the inner surface of said roll for gripping engagement therewith and away from said roll to release the roll, means for urging said gripping member into gripping engagement with said roll, releasing means for moving said gripping member away from the roll to release the roll, supporting means defining an axis of rotation for said reel and supporting said reel for rotation about said axis, means releasably coupling one of said side plates to the other side plate to allow said one side plate to be removed from said other side plate in a direction away from said supporting means, said gripping member and said releasing means being carried by said one removable side plate.

2. In a reel for holding a roll of web material, said reel including spaced side plates between which said roll is disposed; means for gripping said roll to securely hold it on said reel, said gripping means including a gripping member mounted on said reel for movement toward the inner surface of said roll for gripping engagement therewith and away from said roll to release the roll, means for urging said gripping member into gripping engagement with said roll, releasing means for moving said gripping member away from the roll to release the roll, and a lever mounted on said reel, said gripping member including an elongated pin carried by said lever, said pin extending substantially parallel to the longitudinal axis of said reel.

3. The combination according to claim 2, wherein said lever is mounted for rotation about an axis parallel to the longitudinal axis of said reel.

4. The combination according to claim 2, wherein said lever is mounted on the outside face of one of the side plates of said reel.

5. The combination according to claim 2, wherein said lever is mounted on the outside face of one of the side plates of said reel for rotation about an axis parallel to the longitudinal axis of said reel.

6. In a reel for holding a roll of web material, said reel including spaced side plates between which said roll is disposed; means for gripping said roll to securely hold it on said reel, said gripping means including at least two gripping members mounted on said reel for outward movement away from the center of said reel toward the inner surface of said roll for gripping engagement therewith and for return movement toward the center of said reel to release the roll, means for urging said members into gripping engagement with said roll, releasing means for moving said gripping members away from the roll to

release the latter, said releasing means comprising a pair of spaced opposed manually engageable members movable toward each other, and means effective to move said gripping members away from said roll in response to movement of said manually engageable members toward each other.

7. The combination according to claim 6, wherein said means effective to move said gripping members away from said roll comprises a pair of levers, each of said levers having mounted thereon one of said gripping members and one of said manually engageable members.

8. In a reel for holding a roll of web material, said reel including spaced side plates between which said roll is disposed; means detachably coupling said side plates together, latching means for maintaining said side plates

5

coupled together, gripping means movable in a given direction to securely hold said roll on said reel, and a single spring connected between said latching means and said gripping means, said spring being effective to operate said latching and gripping means.

9. The combination according to claim 8 wherein said latching means includes a latching member movably mounted on one of said side plates and said gripping means is mounted on the same said one side plate.
